US00D331573S

United States Patent [19]
Iino

[11] **Patent Number:** **Des. 331,573**
[45] **Date of Patent:** **** Dec. 8, 1992**

[54] **EXPANSION UNIT FOR THE EXTENSION
OF ELECTRONIC COMPUTER FUNCTIONS**

[75] Inventor: **Masaaki Iino, Yokohama, Japan**

[73] Assignee: **Kabushiki Kaisha Toshiba,
Kanagawa, Japan**

[**] Term: **14 Years**

[21] Appl. No.: **675,467**

[22] Filed: **Mar. 26, 1991**

[52] U.S. Cl. **D14/107**
[58] Field of Search **D14/100, 107, 114;

CLAIM

The ornamental design for an expansion unit for the extension of electronic computer functions, as shown and described.

DESCRIPTION

FIG. 1 is a top front and left side perspective view of an expansion unit for the extension of electronic computer functions showing my new design:

FIG. 2 is a front elevational view thereof;

FIG. 3 is a top plan view thereof;

FIG. 4 is a right side elevational view thereof;

FIG. 5 is a rear elevational view thereof;

FIG. 6 is a bottom plan view thereof; and,

FIG. 7 is a right side elevational view thereof showing supporting leg in extruded position.
